UNITED STATES PATENT OFFICE.

EDWIN M. WINTER, OF NEW YORK, N. Y.

BUILDING CONSTRUCTION.

Application filed December 14, 1927. Serial No. 239,968.

My present invention relates to an improvement in building construction and has for its specific object an improvement in the structure and method of assembly of small houses of the so-called suburban type, although it need not be so limited.

One of the main objects of my invention is to eliminate, so far as is possible, the use of wood in the constructional detail of houses, 10 accomplishing greater economy in building, rendering such buildings substantially fire-proof and facilitating ease of erection.

Another object of my invention is the provision of means whereby such buildings may 15 be constructed of metal framing and finished with an erectable, sectional, enclosing structure, made of concrete, pre-cast in molds, and separately applied thereby forming the outer walls thereof of co-operating panel units.

20 A further object relates to the method of co-ordinating the concrete panels with the metal framing of the building and each other, and the flooring, including similar finishing details, to embody a completed structure.

These and other capabilities will be ascertained as the description proceeds, and it is obvious that modifications may be made herein without departing from the spirit of 30 my device or the scope of the appended claims.

In the drawings:

Fig. 1 is a fragmentary transverse section of my structure, taken on the line 1—1, Fig. 35 4, looking in the direction of the arrows.

Fig. 2 is a fragmentary sectional view of a characteristic two-story construction to show details.

Fig. 3 is an enlarged view of the panel 40 locking means.

Fig. 3^a is an enlarged view of an alternate form of panel locking means, similar to that shown in Fig. 3.

Fig. 4 is a front view of two units of 45 panels as applied.

Fig. 5 is a fragmentary view showing the manner of assembling the panels to the uprights.

Fig. 6 is a reduced perspective view of 50 structural iron framing as arranged to carry out my invention.

In my present construction the framing of the house is done with standard structural steel angles, channels and I-beams of 55 suitable dimensions, to form a light, extremely rigid skeleton structure 1, Fig. 6, of suffi-

cient strength to meet the known stresses encountered. All connecting joints between the framing members 2 are riveted or bolted together in the approved present day practice.

In building the metal frame structure generally denoted by 1, Fig. 6, consideration is given to the framing design so that the uprights 2, all figures, are spaced apart at predetermined spacings, in my practice, about five feet apart, this dimension proving suitable in that multiples of this spacing readily meet present day housing dimensions, thus a house twenty feet wide by thirty feet long 70 requires five uprights, including the corner uprights on the shorter dimension, and seven uprights including corner uprights, on the longer dimension, all of said uprights being spaced on five foot intervals.

The height of the ceiling framing and plates 3 for the first and subsequent stories of the building may be made of uniform dimensions, as will hereinafter be explained.

In the erection of my improved structure 80 the usual foundations are laid with or without a cellar, and upon this foundation, not shown, is laid I-beam sections of suitable dimensions, Fig. 6, to form sills 4 for mountably receiving the general house framing 85 structure, also of various sizes, to suit, of structural iron.

To these sills 4 is mounted a plurality of uprights 2 riveted, bolted or otherwise 90 suitably anchored thereto to form struts to support the upper structure of the building, and to act also as anchorages, to be embedded into to support the outer wall structures in the form of panelling 5 and 6, to be later described.

To the upper ends of the uprights 2 is affixed the plates 3 for the first story, and upon these latter a second set of uprights 6 are fixedly mounted, to be completed by plates 7 and a suitable roof framing, generally denoted by 8, which may also be of light iron construction of suitable dimensions and design.

Thus, upon completion of the framing 1, the structure is ready to receive the 105 panelling 5 and 6, which forms the outer enclosing walls of the structure and which panelling, in its assembled position upon the frame structure of the building, may be molded upon its exterior to imitate various 110 finishes, to be painted or not, and upon its interior wall forming surfaces to be treated

in any manner for desired interior wall finish and decoration.

To this end the foundation sills 4 are first molded into a concrete body 9, Fig. 2, which 5 concrete surrounds the iron sills 4 and the bottoms of the uprights 2, the concrete metal-reinforced complete sill having an up-standing ledge 10 molded thereon to act as a support and stop, upon which molded concrete floor forming slabs 11 are abutted, as 10 indicated in Fig. 2. After completion to this point, the structure is then ready for the erection of the wall forming panels 2 thereabout, and this will be later described.

15 Thus, the framing will be so erected that the uprights 2 or other similar functional elements, are spaced to receive and support a series of concrete panels 5 and 6 of unit sizes, that is to say, each panel forming the 20 outer and inner enclosing wall structure is of the same dimensional proportions, each being five feet wide by possibly nine feet high. It is understood that the dimensions herein noted are merely illustrative and that 25 they can be varied to suit, in carrying out my invention.

Each of said panels 5 is provided with suitable edge recesses 12 and formations 13 whereby they coordinate with the uprights 30 2, the plate forming beams 3 and 7, Fig. 2, the floor forming element 11 and the sill 9, thereby to complete the assembly. To this end, the panels 5 are provided on their opposite sides, Figs. 1 and 3, with inverted 35 angular keyways 14, formed by two outstanding enclosing ribs 15 and 16, which extend from the sides of the panel 5. These panels when in associate assembly, as in Figs. 1, 3 and 3^a, are in side contact with each 40 other and enclose, by the association of the panel keyways 14 and completely surround the uprights 2. The exposed contact edges of the adjacent panels may be pointed up to present an unbroken outer wall surface.

45 The upright enclosing chamber, generally denoted by 17, which surrounds the uprights 2, is then filled with a grouting of cement, thus firmly keying the uprights 2 and panels 5 to each other in a firm and weather-tight 50 manner. The exterior faces of the panels are in perfect alinement when assembled and matched as above described and the complete, exterior wall assembly and appearance of the structure compares favorably 55 with any type of exterior made by other methods. Advantage is taken, in molding the panels 5 that the exterior, exposed surface may be of any suitable imitation, such as clap-board, rough or smooth stucco, 60 pebble dash or brick finish, so that buildings erected by my methods have any desired typical exterior appearance and finish, depending upon the kind of mold used in forming the exposed or weather 65 surface of the panels.

In Fig. 3^a a construction of panel and upright jointure is shown enlarged and in fragmentary horizontal section. Herein is disclosed an additional panel locking means whereby the panels are interlocked to each other in addition to grouting to the uprights, as above described, wherein suitably formed dowels 21—21 are set into the associate panel edges at desired points to keep panels alined and to aid in alinement 75 during assembly.

The panels 5 are pre-cast and seasoned and, preferably, brought complete, ready for erection to the erection job and set in position.

80 As previously described, such panels are made in unit sizes, and are in every exterior detail substantially alike, except that those panels selected to carry window and door openings, in which event such panels as A, 85 Figs. 1 and 4, are provided with suitable openings into which door and window casings may be set after erection, or into which cooperative casing parts such as 18, Fig. 1, may be molded when the panels are poured, 90 in the first instance. The type of window illustrated in the drawings herewith is of standard metal frame construction known as the "fenestra" and is used by way of illustration, but any standard type of window 95 construction may be substituted.

99 In order to enable the easy erection of the panels 5 into operative position between the uprights and to care for the joining of the panels at the corner junctures, the keyways 100 14, as will be noted in Figs. 3 and 5, are left considerably longer and larger than the uprights 2, so that the panels may be assembled as illustrated in Fig. 5 which shows the mode of erecting the adjacent corner 105 panels. To this end, the panels are slid onto the uprights 2 the full length of the keyways 5 as at B, Fig. 5, in a diagonal position, till the bottom 8 of the keyway 5 rests against the upright 2, then the panel is 110 swung inwardly in the direction of the arrow C, till its keyway 5 contacts with corner upright 2. At this corner point, as will be ascertained, the panels 5 are mitred as at H, 115 Figs. 1 and 5.

Then the corner panels are slid forwardly as per the arrow D, Fig. 5, which illustrates the second movement of erection, applied to the associate corner panel 5E, Fig. 5, clear 120 of the intermediate upright 2E. Thereafter the intermediate side panels, as in Fig. 1, are positioned between the other uprights 2, and after assembly into the foregoing positions the complete assembly of corner and end panels are moved backwardly until the 125 uprights 2 occupy the central position within all the associate panels, as shown in Fig. 3, and also in Fig. 1. The grouting of the various panels to the uprights 2 through filling of the keyways 14 is then completed, 130

thus bonding the panels to the upright framing 2, thereby making a single rigid unitary wall structure.

It is to be noted that with the end panel 5 in the position shown in Figure 5 at D this panel is clear of the upright 2E so that the remaining panels of this side may be assembled clear to the other end panel of the side. Then after these panels have all been 10 assembled and aligned they are slid against the direction of the arrow D until the recess 14 laps half of the upright 2E. In this manner the corner panels can be assembled on the corner uprights. Obviously the 15 grouting is then applied and locks the parts against further movement in any direction.

After the erection of the first and second story panel structures, the second story 20 flooring 19 may be molded about the girders forming the metal skeleton flooring structure by the usual methods of building wooden forms thereabout and pouring the concrete to form such floor structure utilizing 25 metal reinforcing rods, not shown, in the usual practice. In this operation, the floor forming concrete is molded about the cross girders or sleepers 20, by the conformity of the wooden mold forms, not shown, and concrete is also poured into the lower and upper 30 recesses 13—13 formed in the top and bottom edges of the panels 5, as in Fig. 2, these latter two recesses providing a space to clear the plate forming girders 3. Thus, the second or additional floors are molded about 35 the floor girders, plates and engageably keyed or bonded to the panels 5 forming an integral binding structure between the coordinate panels, girders and floors.

I make no claim as to the novelty of the 40 structural iron framing of the building except as to its coordination with the panelling to accomplish my purpose.

Any desired type of roof may also be used 45 with my structure and I make no claim for novelty therefor.

All partitions within the structure, to divide the same into various rooms, etc. are also erected in the same manner, as described 50 for the exterior walls, and it is thought that this all enters into the general scope of my invention, and need not be shown or described in detail.

The interior partitions, walls and floors may be finished in any desired manner.

Having thus described my invention, what I claim is:

1. In combination, a structural steel frame comprising a row of uprights; panels between and spaced from the uprights and each provided in each side edge face with a deep edge recess forming outer and inner ribs spaced from the uprights and disposed outwardly and inwardly of the uprights, each rib engaging the corresponding rib of the adjacent panel thereby to form chambers

completely enclosing the uprights; and a hardened filler filling said chambers and keying adjacent panels to the adjacent uprights and each other.

2. In combination, a structural steel frame 70 comprising a row of uprights; and panels between and spaced from the uprights and each provided in each side edge face with a deep edge recess forming outer and inner outstanding enclosing ribs spaced from the 75 uprights and respectively disposed outwardly and inwardly of the plane of the uprights, the edge face of each rib engaging the corresponding edge face of the adjacent panel thereby to form upright chambers 80 completely enclosing the uprights.

3. In combination, a structural frame 85 comprising a row of uprights; panels between and spaced from the uprights and each provided in each side edge face with a deep edge recess forming a rib spaced from the uprights and disposed on the same side of the plane of the uprights, each rib engaging the corresponding rib of the adjacent panel thereby to form a continuous wall 90 face and a hardened filler filling said recesses, and securing adjacent panels to each other and the uprights.

4. In combination, a row of structural 95 steel uprights; panels between and spaced from the uprights and each provided in each side edge face with a deep edge recess forming outer outstanding enclosing ribs spaced from the uprights and disposed outwardly 100 of the plane of the uprights, the edge face of each rib engaging the corresponding edge face of the adjacent panel thereby to form a substantially unbroken wall face and recesses partially enclosing the uprights; and a hardened filler filling said recesses for keying 105 adjacent panels to the adjacent uprights and each other.

5. In combination, a row of structural 110 steel uprights; panels between and spaced from the uprights and each provided in each side edge face with a deep undercut edge recess forming outer and inner ribs spaced from the uprights and disposed outwardly and inwardly of the uprights, each rib engaging the corresponding rib of the adjacent panel thereby to form chambers; and a hardened filler filling said chambers and keying adjacent panels to each other and the uprights.

6. In combination, a reinforced plastic 120 sill; metallic I-beam uprights equally spaced apart on said sill with their webs in the vertical planes of the sill; panels mounted on said sill between and spaced from the uprights and each provided from top to bottom of each side edge face with a deep edge recess of dove-tail horizontal section forming outer and inner outstanding enclosing ribs spaced from the uprights and respectively disposed outwardly and inwardly of the 125 130

plane of the uprights; the edge face of each rib substantially engaging the corresponding edge face of the adjacent panel to form an unbroken wall face; and hardened cement grouting integrally filling said recesses in contact all around the faces of the recesses and the uprights and keying adjacent panels to the adjacent uprights and each other.

10 7. In combination, reinforced plastic sills meeting to form corners; a metallic I-beam upright on said sills at the corner; panels mounted on said sills near and spaced from the upright and each provided from top to bottom of the edge face adjacent to the upright, with a deep edge recess forming outer and inner outstanding enclosing ribs spaced from the upright and respectively disposed outwardly and inwardly of the upright, the edge face of each rib engaging the corresponding edge face of the adjacent panel at an angle of 45 degrees to the plane of the respective panels; and hardened cement grouting integrally filling said recesses in contact all around the faces of the recesses and the upright and keying adjacent panels to the adjacent uprights and each other.

8. In combination, reinforced plastic sills meeting to form corners; metallic I-beam uprights equally spaced apart on said sills intermediately thereof and at the corners respectively, with their webs in the vertical planes of associated sills; panels mounted on said sills between and spaced from the uprights and each provided from top to bottom of each side edge face with a deep edge recess of dove-tail horizontal section forming outer and inner outstanding enclosing ribs spaced from the uprights and respectively disposed outwardly and inwardly of the plane of the uprights, the edge face of each rib engaging the corresponding edge face of the adjacent panel to form an up-

right chamber and an unbroken wall face; the edge faces meeting at the corners being 45 disposed at 45 degrees to the plane of their respective panels; and hardened cement grouting integrally filling said recesses in contact all around the faces of the recesses and the uprights and keying adjacent panels 50 to the adjacent uprights and each other.

9. A building comprising a structural steel framing having spaced uprights, wall forming elements consisting of panels extending between adjacent uprights and having channeled side edges fitting around said uprights, the channels of adjacent panels entirely enclosing said uprights, and grouting filling the space within the channels and around the uprights.

10. A building comprising a structural steel framing having spaced uprights, wall forming elements consisting of panels extending between adjacent uprights and having side edges fitting around said uprights, the side edges of adjacent panels entirely enclosing said uprights, and grouting filling the space between the side edges and around the uprights.

11. A building comprising a structural 70 steel framing having uprights spaced at unit intervals, wall forming elements consisting of panels of unit width and each extending between adjacent uprights and having channeled side edges fitting around said uprights, 75 the channels of adjacent panels entirely enclosing said uprights, and grouting filling the space within the channels and around the uprights, said grouting locking the adjacent panels together and to said uprights whereby the uprights constitute reinforcing for the panels.

Signed at New York, in the county of Westchester and State of New York, this 12th day of December, A. D. 1927.

EDWIN M. WINTER.
